NOISE ELIMINATOR FOR TELEPHONE TRANSMITTERS

Filed Dec. 16, 1943

UNITED STATES PATENT OFFICE

2,425,061

NOISE ELIMINATOR FOR TELEPHONE
TRANSMITTERSHarry J. Hart, Baldwin Township,
Allegheny County, Pa.

Application December 16, 1943, Serial No. 514,475

8 Claims. (Cl. 179—188)

1

My invention relates to telephones, and consists in an appliance for excluding extraneous noises from the transmitter of a telephone instrument.

A sound-excluding or eliminating appliance of the type to which this invention relates consists essentially in perforated sound screen that is adapted to be secured over the transmitter of a telephone instrument. Organized with the sound screen is a shutter which by manipulation may be caused to close the perforations in the screen. Thus, when the user of the telephone is not talking, he may exclude all sound from the transmitter of the telephone instrument, with the effect that he obtains better reception of the message transmitted to him. Of course, when the user of the telephone is speaking, the shutter is so positioned as to uncover the perforations. In general, an appliance or device of this sort is years old in the art, and it is to be understood that my invention relates to certain new and useful improvements in the construction of such an appliance and in the particular structural organization of the appliance with a modern telephone instrument, whereby the appliance becomes commercially practical and valuable.

The invention will be understood upon reference to the accompanying drawings, in which:

Figure 1 is a view in front elevation of the receiver-transmitter unit of a modern telephone instrument. The unit is shown held in the hand of a user, and on the transmitter portion of the unit is shown a sound-eliminator of the present invention;

Figure 2 is a view in plan and to larger scale of the outer side of the sound-eliminator;

Figure 3 is a view in plan of the same as seen from the inner side;

Figure 4 is a view in medial section and to still larger scale of the sound-eliminator, the transmitter portion of the receiver-transmitter unit on which the device is adapted to be secured being shown in broken lines; and

Figure 5 is a fragmentary view, corresponding to Figure 4, and illustrating a modification or elaboration in structure.

Referring to the drawings, the reference numeral 2 is applied to the receiver-transmitter unit of a conventional telephone instrument, and 3 indicates generally a sound-eliminator of the invention. The sound-eliminator comprises a cap that includes a perforate diaphragm portion 4 having a skirt portion 5 provided internally with a peripheral bead 6 that engages the usual groove 7 (Figure 4) formed in the cover or housing 8 on

2

the transmitter portion of the receiver-transmitter 2. As thus secured on said transmitter portion, it will be understood that the diaphragm portion 4 provides a sound screen over the perforate face of the transmitter housing or casing 8. Means are provided for opening and closing the perforations of the sound screen, whereby the sound screen may, at the will of the person using the telephone, be effective to exclude sound from the transmitter, or to permit the entrance of sound, i. e., sound waves.

Such means comprise a perforate shutter disk 9 mounted within the body 4, 5 to turn on a post 10. The shutter disk is provided with an arm 11 extending through a circumferential slot 12 in the skirt portion 5, and as thus extending the arm 11 is accessible to the finger F of the hand of the person using the telephone. The sound-eliminator is, it will be seen, so positioned on the transmitter portion of the telephone unit 2 that the arm 11 may be readily manipulated by the finger F of the hand that holds the receiver-transmitter unit of the telephone, whereby the other hand of the telephone user remains free to write memoranda, etc., while using the telephone. This is an important advantage of the structural organization of my invention.

The perforations 13 in the shutter 9 are identical in form and arrangement to the perforations 14 on the screen 4, and a torsion spring 15, secured in a suitable kerf in the post 10, includes two oppositely extending portions having upturned tips 15a (Figures 4 and 5) that are lodged in two of the perforations 13 in the shutter disk, the spring being stressed before the tips are sprung into the perforations. The spring exerts a constant torsional stress, tending to rotate the shutter clockwise, as it appears in Figure 2. Under the stress of the spring the shutter is normally maintained in a position with the arm 11 bearing against the right-hand end of the slot 12 (Figures 1 and 2), and in such position the perforations or orifices 13 and 14 of the shutter and screen, respectively, stand in exact registry (see Figure 4), whereby the voice of a person speaking into the transmitter of the telephone instrument is clearly transmitted over the telephone system. Alternately, when the telephone user is listening to a message received by the receiver portion 80 of the unit 2, he presses his finger against the arm 11 and thereby turns the shutter 9 into a position in which the body portions of the shutter between the perforations 13 close all of the perforations 14 in the screen 4. Thus, the screen 4 becomes an impervious diaphragm,

excluding all external noises from the transmitter portion of the telephone instrument, whereby the telephone circuit is protected from the effect of extraneous sound waves. The spring 15, anchored to the post 10 serves in a second capacity; that is, it serves to secure the shutter 9 in assembled position upon the post 10.

At this point it may be noted that the particular arrangement and graduated size of the perforations in the screen 4 and shutter 9 are important. The perforations adjacent the common center of the assembled members 4 and 9 are smallest, there being an inner ring of nine perforations of $\frac{1}{16}$ " in diameter. Outward from such inner ring is a second ring of nine perforations of $\frac{1}{8}$ " in diameter; outward from the second ring is a third ring of nine perforations of $\frac{3}{16}$ " in diameter, and finally the fourth or outermost ring includes nine perforations of $\frac{1}{4}$ " in diameter. The perforations in the second ring are staggered with respect to the perforations in the first or inner ring; the perforations in the third ring are staggered with respect to those in the second ring, and those of the fourth with respect to those of the third, all as clearly indicated in the drawings. The essential thing is that the area of the openings in the screen and shutter shall be distributed radially and circumferentially of the center of the assembly, and the effective area of the openings is greater according as the radial distance of the openings from said center is greater.

A valuable feature of the structure comprises a gasket 9b that is secured in a peripheral channel 9a in the shutter disk 9. This gasket is formed of a compressible, sound-absorbing material such as felt. When the sound-eliminating device is assembled in service position, this gasket bears upon the surface of the transmitter housing 9 (Figure 4). The gasket encompasses the usual perforations (not shown) formed on the face of the transmitter housing, and insures the exclusion of all sound waves therefrom, except the sound waves that are intentionally permitted to pass through the perforations 13 and 14. The gasket 9b while affording sound-tight assembly of the device upon the transmitter housing, in no way interferes with the desired manipulation of the shutter disk.

The acoustic properties of the device are further enhanced by the provision of a coating 9c (Figure 3) of sound-absorbing material upon the inner face of the shutter disk. This coating may comprise small particles of felt dusted upon a film of adhesive, such as a resinous glue, applied to the surface of the disk.

An important feature of the sound-eliminator of my invention consists in its structural form which permits manufacture from a plastic material, particularly a molding or moldable plastic material. Any one of the several known molding plastic materials may be used, say urea formaldehyde, or a phenolic, a vinyl, or other suitable resin. Manifestly, the shutter disk 9 may be readily produced in a plastic-molding press. In the case of the portion 4, 5 of the device, the molding operation may be facilitated by the provision of a plurality of slits 16 that opens inward from the rim of the skirt portion 5. The slits are herein shown to be four in number, spaced ninety degrees apart. By virtue of these slits the molded body 4, 5 may be more readily stripped from that die portion of the molding press which includes the groove for forming the bead 6 on the skirt, the molded and cured plas-

tic material possessing adequate elasticity to permit such stripping away of the formed article. Additionally, and of at least equal importance, the provision of the slits 16 provides in the skirt 5 a yieldability that more readily permits the skirt to expand radially as the device is applied to the transmitter portion 8, and when the bead 6 reaches the groove 7 in the portion 8, the inherent elasticity of the skirt causes the expanded skirt to contract, locking the bead 6 in the groove 7. Security of attachment of the applied sound-eliminator is thus obtained.

In elaboration of the structure described, I provide a detent 17 in the body of the sound-eliminator. This detent comprises a pin organized with a spring 18 that tends to hold the pin in its illustrated position. The inner end of the pin is provided with a head 19 that provides an abutment limiting the outward movement of the pin under the stress of spring 18. The pin is so located in the path of movement of the arm 11 of the shutter, that when the shutter is moved into closed position, the pin may be pressed inward to engage the arm 11 and prevent the shutter from returning to normal position in which the perforations 13 and 14 stand in registry. When the pin is thus pressed inward, the head 19 on the pin latches beneath the engaged edge of the arm 11, and holds the pin, against the stress of spring 18, in arm-engaging position. When the shutter is locked in closed position, there will be a slight clearance between the end of slot 12 and the adjacent edge of arm 11, so that to release the shutter it will be merely necessary to press the arm 11 in shutter-closing direction through the interval permitted by said slight clearance, such movement of the arm releasing the engagement of the pin head 19 with the arm, whereby the pin returns to normal position under the effect of spring 18.

The provision of the detent 17-19 permits the user of the telephone to lock the shutter in closed position for an interval of time, as may be desirable when the user must interrupt a telephone conversation and lay the receiver-transmitter unit 2 aside while he looks up certain information or performs some task. In this way the telephone circuit may be protected from the noises prevailing in the room in which the telephone instrument is located. The reader need only to call to mind the noise in a machine shop, or the like, to appreciate the value of the structure described.

Within the terms of the appended claims many modifications and variations are possible, without departing from the spirit of the invention.

I claim as my invention:

1. An appliance for a telephone transmitter having a casing that includes a perforate circular face and a circumferential groove in the annular side of the casing surrounding said face, said appliance comprising a cap member adapted to be assembled over said transmitter casing, said cap member having a perforate diaphragm portion arranged in assembly to overlie the perforate face of said casing and a radially expandable elastic skirt portion extending peripherally of the diaphragm portion, said skirt portion carrying at its periphery means for yieldingly engaging said groove in said casing to secure the cap member in assembly therewith.

2. An appliance for a telephone transmitter having a casing that includes a perforate circular face and a circumferential groove in the annular side of the casing surrounding said face,

said appliance comprising a cap member adapted to be assembled over said transmitter casing, said cap member comprising an integrally molded body of plastic material having a perforate diaphragm portion arranged in assembly to overlie the perforate face of said casing and a radially expansible elastic skirt portion extending peripherally of the diaphragm portion, said skirt portion including a plurality of slots extending inward from the edge thereof at circumferentially spaced-apart points, the slotted skirt portion carrying at its peripheral edge means for yieldingly engaging said groove in said casing to secure the cap member in assembly therewith.

3. In the combination of a receiver-transmitter telephone unit and a noise eliminator including a perforate sound screen applied upon the transmitter portion of said unit, said noise eliminator including a shutter movable between alternate positions to open and close the perforations in said screen, a sound-absorbing gasket carried by the periphery of said movable shutter and bearing upon the body of the transmitter portion of said unit, a torsion spring urging said shutter into one of said positions, said shutter having a member extending therefrom in position to be manipulated by a finger of the hand holding the receiver-transmitter unit in service to move said shutter into the other of said positions.

4. In the combination of a receiver-transmitter telephone unit and a noise eliminator including a perforate sound screen applied upon the transmitter portion of said unit, said noise eliminator including a shutter movable to open and close the perforations in said screen, a sound-absorbing gasket carried by the periphery of said movable shutter and bearing upon the body of the transmitter portion of said unit, a coating of sound-absorbing material carried by said shutter, said shutter having a member extending therefrom in position to be manipulated by a finger of the hand holding the receiver-transmitter unit in service.

5. In combination a receiver-transmitter telephone unit and a noise eliminator including a perforate sound screen applied upon the transmitter portion of said unit, said noise eliminator including a shutter movable to open and close the perforations in said screen, a spring normally urging said shutter into perforation-open-

ing position, and means included in the noise eliminator structure for temporarily locking said shutter against spring tension in closed position.

6. An appliance for a telephone transmitter whose perforate mouth-piece includes a peripheral groove, said appliance comprising a perforate sound screen having an elastic skirt including a rib adapted to engage said groove in the mouth-piece, and a manually operable shutter for opening and closing the perforations in said screen, said movable shutter carrying a sound-absorbing gasket bearing slidably upon the mouth-piece in encompassing relation with respect to the mouth-piece perforations.

15 7. An appliance for a telephone transmitter having a perforate mouth-piece, said appliance comprising a perforate sound screen and means for securing it upon said perforate mouth-piece, and a manually operable shutter for opening and closing the perforations in said screen, said movable shutter carrying a sound-absorbing gasket bearing slidably upon said mouth-piece in encompassing relation with respect to the mouth-piece perforations.

20 8. An appliance for a telephone transmitter having a perforate mouth-piece, said appliance comprising a perforate sound screen and means for securing it upon said perforate mouth-piece, a manually operable shutter for opening and closing the perforations in said screen, a spring normally urging said shutter into perforation-opening position and means included in the appliance structure for temporarily locking said shutter in against spring tension position with the screen perforations closed.
